UNITED STATES PATENT OFFICE.

ALEXANDER MARR, OF LONGSIGHT, ENGLAND.

APPARATUS FOR THE REPRODUCTION OF SOUND.

1,325,878.

Specification of Letters Patent. Patented Dec. 23, 1919.

Application filed November 13, 1917. Serial No. 201,728.

To all whom it may concern:

Be it known that I, ALEXANDER MARR, a subject of the King of Great Britain and Ireland, and a resident of Longsight, Manchester, in the county of Lancaster, England, have invented certain new and useful Improvements in or Relating to Apparatus for the Reproduction of Sound, of which the following is a specification.

10 This invention relates to apparatus for the reproduction of sounds, particularly to telephone receivers, and has special reference to the ordinary flat or disk diaphragm which is clamped around or near its periphery.

According to the invention, the parts between which an ordinary flat or disk diaphragm is clamped around or near to its periphery are formed so that two or more 20 pairs of narrow or knife-edge like surfaces result between which the diaphragm is clamped.

In the accompanying drawing, Figure 1 is a part sectional view of a telephone receiver illustrating one embodiment of the invention and Figs. 2, 3, 4 and 5 are similar views of modifications thereof.

Referring first to Figs. 1 and 2, the ends of the receiver body *a* and cap or ear-piece *b* are grooved or otherwise formed so that two pair of narrow or knife edge-like surfaces *a*¹, *b*¹ and *a*², *b*², result between which the diaphragm *c* is clamped on the screwing up of the cap or ear-piece *b*. When the 35 clamping means are each merely provided with a single circular knife-like edge, and these edges should not accurately oppose one another, distortion of the diaphragm would result which would materially impair the sound-producing efficiency of the instrument. By means of two or more concentric knife edge-like surfaces, such distortion of the diaphragm *c* is guarded against and the surface engaged is not materially increased.

45 Instead of the clamping surfaces *b*¹, *b*², being formed on the cap or ear-piece *b* as in Figs. 1 and 2, they may, as shown in Fig. 3, be formed on a ring *b*³ fitted in the cap or ear-piece, and, if necessary, a ring *d* of 50 metal, ebonite, fiber or other suitable material may be fitted conveniently on a ledge on the ring *b*³, as shown, to adjust the size of the air space. Preferably, however, the ring *b*³ is of triangular or beveled section 55 with its outer periphery parallel to its axis

and its inner periphery inclined, as illustrated in Fig. 4, and the cap or ear-piece *b* is provided with a correspondingly shaped groove in which the ring *b*³ fits and the clamping surfaces *b*¹, *b*² on the latter are 60 cemented or otherwise appropriately attached to the diaphragm *c*, so that the screwing up of the cap or ear-piece not only securely clamps the diaphragm, but also accurately centers same with respect to the 65 magnet *e*.

In the embodiment illustrated in Fig. 5, the body *b* is fashioned with three concentric knife-edge like surfaces *b*¹, *b*² and *b*⁴, and the body *a* with a like number of complementary surfaces *a*¹, *a*² and *a*³ so that the diaphragm is clamped between three pair of knife-edged surfaces, viz:—*a*¹ *b*¹, *a*² *b*² and *a*³, *b*⁴.

It will be seen that in all cases the diaphragm is clamped circumferentially at two or more points spaced radially, one point of clamping being at or near the periphery of the diaphragm and the other or others at a little distance therefrom and 70 from each other, and between these points the diaphragm is unclamped. Such manner of clamping the diaphragm considerably reduces the damping due to clamping and permits the diaphragm to attain a greater 75 amplitude of vibration with greater efficiency in sound reproduction than when it is clamped as ordinarily over a comparatively large radial area.

What I claim as my invention and desire 80 to secure by Letters Patent is:—

1. In apparatus for the reproduction of sound, a vibrating diaphragm, and a plurality of pairs of opposed knife-edge like clamping surfaces directly in engagement 85 with, and between which said diaphragm is clamped circumferentially at a plurality of radially-spaced points.

2. In apparatus for the reproduction of sound, a body, a support on said body, a 100 clamping member, a plurality of concentric narrow or knife-edge like clamping surfaces on said support, a plurality of concentric knife-edge like clamping surfaces on said clamping member arranged opposite to 105 those on said support, and a vibrating diaphragm directly in engagement with and clamped between said pluralities of clamping surfaces.

3. In apparatus for the reproduction of 110

sound, a body, a support on said body, a plurality of knife-edge like clamping surfaces on said body, a cap on said body, a beveled ring in said cap, a correspondingly beveled surface on said cap against which the beveled face of said ring bears, a plurality of narrow or knife-edge like surfaces

on said ring opposite to those on said support, and a vibrating diaphragm clamped between said pluralities of clamping surfaces and secured to those on said ring. 10

In witness whereof I have hereunto set my hand.

ALEXANDER MARR.
